UNITED STATES PATENT OFFICE.

ALFRED M. ACKLIN, OF PITTSBURG, PENNSYLVANIA, ASSIGNOR TO HEYL AND PATTERSON, INCORPORATED, OF PITTSBURG, PENNSYLVANIA, CHARTERED UNDER THE LAWS OF PENNSYLVANIA.

ROPE-CLAMP.

SPECIFICATION forming part of Letters Patent No. 783,564, dated February 28, 1905.

Application filed August 4, 1904. Serial No. 219,568.

To all whom it may concern:

Be it known that I, ALFRED M. ACKLIN, a resident of Pittsburg, in the county of Allegheny and State of Pennsylvania, have invented a new and useful Improvement in Rope-Clamps; and I do hereby declare the following to be a full, clear, and exact description thereof.

My invention relates to rope-clamps, and more especially to rope-clamps used in connection with conveying mechanism where it is desired to drive the conveyer by means of an endless cable, its object being to provide a rope-clamp which will not engage the driving pulleys or sheaves, thereby providing for a more even movement of the conveyer and involving less wear and tear upon the pulleys or sheaves.

To these ends my invention comprises the novel features hereinafter set forth and claimed.

To enable others skilled in the art to make and use my invention, I will describe the same more fully, with reference to the accompanying drawings, in which—

Figure 1 is a portion of a conveyer and pulley or sheave, showing my improved clamp as applied to the cable passing around said pulley. Fig. 2 is a cross-section on the line 2 2, Fig. 1; and Figs. 3, 4, and 5 are details of my improved clamp.

Like numerals indicate like parts in each figure.

I have illustrated my invention in connection with a conveyer device such as is suitable for conveying kegs of nails, flour, or other material from one point to another, and as my invention relates only to the clamping device I have only illustrated one section of such a conveyer. The track on which the conveyer travels consists of the channel-beams 2, facing each other, the lower flanges of said channel-beams acting as rails or supports for the wheels 3 of the conveyer-trucks or carriages. Supported on the trucks are the pans or trays 5, which in the form illustrated are slightly curved, so as to conform to the shape of a keg or barrel, and said pans are provided with suitable projections 6, which are adapted to

prevent the slipping of the keg or barrel. In order to drive the conveyer, the cable 7 is employed, which is connected to the trucks at or adjacent to the mid-point, as indicated.

Depending from the truck 4 and secured thereto is the bracket 8, through which passes the pin 9, held in place by the split keys 10. A strap or stirrup 11, U-shaped in form, is supported by the pin 9, and inclosed by said strap is the wedge-block 12. The cable 7 rests in the closed end of the stirrup 11, and interposed between said cable and wedge-block 12 is the clamping-piece 13, said clamping-piece being slightly bow-shaped and conforming on its inner face to the rounded form of the cable 7. A wedge 15 is driven between the block 12 and clamping-piece 13. In assembling the parts this wedge 15 is driven in last and acts to cause the cable to conform to the bow shape of the clamping-piece 13, which draws up the cable at that point, while at the same time the lower end of the hanger 11 and clamping-piece 13 are so elevated as not to engage with the pulley 16, as clearly indicated in Fig. 2.

I have illustrated my invention in connection with the pulley 16 where the cable turns, and in order to make the turn properly at this point a guide-track 17 is employed, with which the wheels 3 of the conveyer-trucks engage. By my invention, therefore, the conveyer-trucks are clamped to the cable, so as to be securely connected thereto, while at the same time the clamps are in such a position as not to engage with the pulleys, and as a consequence a more even running of the conveyer is obtained, while at the same time the wear on the pulleys is greatly reduced.

It is apparent that my invention may be applied to other forms of conveyers with equal facility.

What I claim is—

1. In a rope-clamp, the combination of a stirrup adapted to engage the cable, a clamp in said stirrup and means for creating a bow in the cable at point of clamping.
2. In a rope-clamp, the combination of a stirrup adapted to engage the cable, a bowed clamping-block in said stirrup and means for drawing said cable up to engage said block.

3. In a rope-clamp, the combination of a stirrup adapted to engage the cable, a bowed clamping-block in said stirrup having a curved inner face, and means for drawing said cable up to engage said curved face.

4. In a rope-clamp, the combination of a **U**-shaped stirrup adapted to engage the cable, a bowed clamping-block in said stirrup, and means for drawing said cable up to engage said block.

5. In a rope-clamp, the combination of a **U**-shaped stirrup adapted to engage the cable, a bowed clamping-block in said stirrup, a wedge-block, and a wedge inserted between said clamping-block and wedge-block.

6. In a rope-clamp, the combination of a **U**-shaped stirrup adapted to engage the cable, a bowed clamping-dog in said stirrup having shoulders with which said stirrup engages,

and means for drawing said cable up to engage said clamping-block. 20

7. In a rope-clamp, the combination of a **U**-shaped stirrup adapted to engage the cable, a bowed clamping-dog in said stirrup having recesses engaged by said hanger, and means 25 for drawing said cable up to engage said clamping-block.

8. In a rope-clamp, the combination of a **U**-shaped stirrup, a wedge-block supported within said stirrup, a bowed clamping-block, 30 and a wedge inserted between said clamping-block and wedge-block.

In testimony whereof I, the said ALFRED M. ACKLIN, have hereunto set my hand.

ALFRED M. ACKLIN.
